CLAIM

The ornamental design for a hybrid connector assembly, as shown and described.

DESCRIPTION

FIG. 1 is a front and lower right perspective view of a hybrid connector assembly showing our new design;

FIG. 2 is a front view of the hybrid connector assembly shown in FIG. 1;

FIG. 3 is a rear view of the hybrid connector assembly shown in FIG. 1. The broken lines in FIG. 3 are included for the purpose of illustrating portions of the hybrid connector assembly that form no part of the claimed design.

FIG. 4 is a left side view of the hybrid connector assembly shown in FIG. 1;

FIG. 5 is a right side view of the hybrid connector assembly shown in FIG. 1;

FIG. 6 is a top view of the hybrid connector assembly shown in FIG. 1; and,

FIG. 7 is a bottom view of the hybrid connector assembly shown in FIG. 1.
